Primary Examiner — Rosemary K Tarcza*Assistant Examiner* — Christy Nemeth(74) *Attorney, Agent, or Firm* — Dunlap Bennett & Ludwig PLLC; Brendan E. Squire(57) **CLAIM**

The ornamental design for a charging station, as shown and described.

DESCRIPTION

FIG. 1 is a top front perspective view of a charging station; FIG. 2 is a front elevation view thereof;

FIG. 3 is a rear elevation view thereof;

FIG. 4 is a left side elevation view thereof; the right side view being a mirror image thereof;

FIG. 5 is a top plan view thereof; and,

FIG. 6 is a bottom plan view thereof.

The broken lines shown in the drawings illustrate unclaimed portions of the charging station that form no part of the claimed design.

The dash-dot-dash lines in the drawings illustrate the boundary of the charging station design and form no part of the claimed design.
